UNITED STATES PATENT OFFICE.

JOHN A. SMITH, OF CLEVELAND, OHIO, ASSIGNOR TO ELLIOTT-FISHER COMPANY, OF NEW YORK, N. Y., A CORPORATION OF DELAWARE.

VARIABLE CARRIAGE-FEED FOR TYPE-WRITING MACHINES.

No. 922,584.

Specification of Letters Patent.

Patented May 25, 1909.

Application filed August 23, 1904. Serial No. 221,859.

To all whom it may concern:

Be it known that I, JOHN A. SMITH, a citizen of the United States, residing at Cleveland, in the county of Cuyahoga and State of Ohio, have invented a new and useful Variable Carriage-Feed for Type-Writing Machines, of which the following is a specification.

My present invention relates to typewriting machines, but more particularly to novel carriage feeding mechanism designed with special reference to the equipment of a machine of the flat platen type.

The object of the invention is to produce an efficient carriage feeding mechanism, and to provide for the variable feeding of the carriage in the direction of letter spacing so that wide or narrow spacing appropriate to the characters printed, or to the particular class of work may be secured. It may be explained that in certain machines two distinct alphabets of type are employed, the characters of one being broad and of the other comparatively narrow. In such machines it is desirable to provide a variable carriage feed in order that the letter spaces produced by the step-by-step advance of the carriage may be uniformly wide or narrow, accordingly as wide or narrow characters are printed.

This invention is directed to the attainment of the end stated, but it should also be borne in mind that its utility is not confined to its use in connection with machines equipped with two distinct classes of wide and narrow type, since it is equally useful in printing certain data, as for instance, headings, names, etc., with exaggerated spacing of the letters, irrespective of the particular character of the latter.

In the accompanying drawings—Figure 1 is a rear elevation of a Fisher typewriter equipped in accordance with my invention. Fig. 2 is a sectional plan view of a portion of a machine thus equipped. Fig. 3 is a transverse section through the machine carriage and a portion of its support, the depressed position of the case key and the operative position of the space rack being shown in dotted lines. Fig. 4 is a longitudinal section of the carriage showing its support, the space rack, the escapement and certain other parts in elevation. Fig. 5 is a detail view showing the escapement, with the parts in the positions they assume at the

instant of retardation of the holding dog to permit a double space movement of the carriage. Fig. 6 is a perspective view of the mechanism for controlling the letter space movements of the carriage designed more particularly to show the line of connection between a key and the escapement as well as the connection between the case key and the means for changing the carriage feed. Fig. 7 is a detail view of the trip arm. Fig. 8 is a similar view of the shift rod, and Fig. 9 is a detail sectional view of the rack and trip arm.

The carriage feeding mechanism, while capable of general application to machines embodying an element arranged for intermittent advance, is designed with special reference to the equipment of the Fisher typewriter shown in the drawings, but more fully illustrated in a number of patents, notably No. 573,868 to R. J. Fisher. The Fisher machine is of the flat platen type and it includes a carriage supporting frame 1, mounted to travel in the direction of line spacing upon tracks or guides 2 carried by a platen 2^a the writing surface of which is indicated in Fig. 1. The frame 1 is provided with front and rear carriage guides 3 and 3^a, see Fig. 3, upon which travels in the direction of letter spacing, a carriage 4, supporting a pendent type-bar supporting ring 5 upon which the downwardly acting type-bars 6 are supported.

The carriage 4 is moved to the right by suitable carriage propelling mechanism generally including straps or tapes 7 connected at their outer ends to spring drums 7^a. Movable with the carriage are a pair of carriage pinions 8 and 9 meshing with front and rear feed racks 10 and 11 parallel with and secured to the carriage guides 3 and 3^a of the machine frame. These pinions are mounted upon a common feed spindle 12 extending transversely through the carriage casing and having operative connection with a ratchet or escapement wheel 13 constituting a rack element for what may be termed the escapement proper. Since the spindle 12, which is movable with the carriage, is geared by the pinions 8 and 9 to the fixed racks, it follows that the escapement wheel being operatively connected with the spindle, must rotate when the carriage moves forward in the direction of letter spacing. Therefore, the movement of the carriage is controlled by a pair of

escapement dogs, towit, a holding dog 14 and a spacing dog 15, coöperating with the wheel 13 and constructed and arranged in the manner disclosed in the Fisher patent 5 before identified. Normally, as shown in Fig. 4, the holding dog engages the wheel 13 and holds the same thus preventing the forward movement of the carriage. When, however, the dogs are swung, the holding 10 dog moves out of engagement with the wheel, but before the disengagement is effected, the spacing dog moves into engagement. This movement of the parts is effected by the depression of any one of the letter or 15 numeral keys 16. When the key is released, however, the movement of the dog is reversed, and, while the spacing dog is moving out of engagement with the wheel and before the holding dog moves into engagement 20 therewith, the wheel is permitted to rotate an almost inappreciable distance so that the holding dog instead of moving back into engagement with the flat face of the tooth before engaged by it, will engage the next 25 succeeding tooth when the spacing dog has moved back sufficiently to release the wheel and thus permit a partial rotation thereof and the advance of the carriage the distance of one letter space before the arrest of the 30 wheel is effected by the holding dog.

The operating mechanism between the keys and the escapement includes an arm 17 extending from the spacing dog and connected by a link 18 to an arm 19 projecting 35 from the rock shaft 20 extending longitudinally of the carriage, see Fig. 6. This shaft is vibrated by key yokes 21 mounted to swing within the casing and arranged to be engaged and swung by a pin 22 (one of 40 which is carried by each key stem) just as the key reaches the limit of its downward movement. The complete depression of a key thus effects the swinging of the yoke 21 to rock the shaft 20 and thus shift the escapement dogs, the release of the key serving to permit the dogs to swing back for the 45 purpose of effecting the feed of the carriage, in a manner already stated. To effect the release of the carriage from control by the 50 escapement, the escapement lever 23 (designed to be operated by a carriage release key, not shown) is arranged to move the dogs relatively for the purpose of releasing the escapement wheel entirely therefrom, 55 it being understood that while the dogs are mounted for movement in unison under normal conditions, they are capable of being swung independently, for the purpose indicated.

60 The construction thus far described is ordinary, but an understanding thereof is necessary to a proper comprehension of my improvements. From what has been said, it will be evident that the letter space move- 65 ments of the carriage will be only of such

extent as is permitted by the movement of the escapement wheel 13 the distance of one tooth. This is the normal movement and provides what may be termed normal or narrow spacing. To attain the object of 70 the present invention, it is merely necessary to provide for a greater movement of the escapement wheel 13 upon each actuation of the dogs by the depression and release of the key, since this will obviously effect a proportionate increase of each advance step or movement of the carriage. 75

Connected to or formed as an integral part of the holding dog 14 of the carriage escapement, is an arm 24, the end of which 80 is disposed for engagement by an arm 25 extending laterally from a rock shaft 26 provided with a bearing sleeve 27 extending through the back wall of the carriage casing, see Figs. 3 and 6. At the extremity of 85 the shaft 26 in rear of the carriage is fixed a trip arm 28 having at its end a pointed beak or projection 29 which is arranged to contact with a series of relatively fixed trips 30, preferably in the form of pointed equi-distant teeth defined at the under side or edge of what may be termed a spacing rack 31. This rack while stationary relative to the trip arm when in its normal position, is nevertheless laterally movable in order to 90 permit its presentation in either an operative or an inoperative position. To provide for this movement of the rack, it is carried at the upper ends of a pair of swinging arms 32 having hinged connection with supporting brackets 33 secured to the machine frame 1 at any suitable point, but preferably to the rear side of the guide 3^a. Normally the spacing rack 31 is located in an inoperative position, as shown in full lines in 100 Fig. 3, and when so disposed the trips or teeth 30 are arranged out of the path of the projection 29 on the arm 28 to permit the normal operation of the escapement in the manner described for the purpose of providing normal or narrow letter spacing of the carriage. When, however, it is desired to provide exaggerated or wide spacing, the rack 31 is swung to its operative position, indicated in dotted lines in Fig. 3, the trips or teeth 30 being presented in operative relation with the projection 29 on the arm 28. Now, upon the depression of the key, the action of the dogs is precisely as heretofore described. That is to say, the holding 110 dog moves out of engagement with the wheel 17 and the spacing dog moves into engagement therewith, the wheel being permitted such slight movement during this operation of the parts as will carry the extremity of 115 the wheel/tooth beyond the nose of the holding dog so that upon the return of the latter it cannot engage the same tooth. Upon the release of the key, however, a variation in 120 the action of the escapement may be noticed. 125

As the key rises the spacing dog will move out of engagement with the wheel and the holding dog will simultaneously move toward the wheel for reengagement therewith. As soon as the wheel is released by the spacing dog, it will begin to rotate and the carriage will begin to advance, but just at that instant when, under normal conditions, the holding dog would move into engagement with the next succeeding tooth of the wheel to arrest the carriage at the limit of a normal letter space, the pointed projection 29 in the arm 28 will engage the extremity of one of the trips or teeth 30 which will retard the movement of the holding dog until the extremity of the tooth next succeeding that originally engaged by it has passed the nose of the dog. Owing to the fact that the engaging portions of the trips 30 and projection 29 are pointed, this retardation of the holding dog will be but momentary. This, however, will be sufficient to insure the escape of two teeth of the wheel instead of one and a double or exaggerated movement of the carriage will, therefore, be effected before the holding dog arrests the escapement wheel.

While it is not essential that special means be provided for swinging the spacing rack into and out of position, such movement, as a matter of fact, is effected by means of a key located at the keyboard and, since the change from narrow to wide spacing is desired when the wide or upper case type are brought into action, the case key which effects this rearrangement of the printing mechanism is utilized to shift the spacing rack. The type-bars 6, two of which are clearly shown in Fig. 6 of the drawings, are each equipped 40 with what is known in the art as a plural type head 34 pivotally mounted at the upper free end of the bar and carrying upper and lower case characters 35 and 36. Each type head is normally retained by a trigger 37 in a position which will insure the presentation of the lower case character 36 to the printing point when the type bar is thrown down by the depression of a key.

The trigger 37 is mounted on the type-bar, 50 as shown, and is provided with a cam-shaped tail-piece or trip arm 38 and with a resetting arm 39. Above the trip arms 38 of the several triggers is disposed a trip ring 40, carried by a trip frame 41 secured to a vertically disposed spring-supported stud 42 movable in a vertically disposed guide sleeve 43 suitably mounted in the carriage casing. The trip ring 40 normally occupies a position sufficiently elevated to prevent interference 55 with the trip arms of the triggers when the type-bars are swung down. When, however, it is desired to print an upper case character, or one having a wide face, the trip ring is depressed, so that the trigger of any actuated 60 type-bar will be swung out of engagement

with the type head, by reason of the engagement of the tail-piece 38 of said trigger with the type ring during the initial movement of the bar. The tripping of the trigger in this manner and the consequent release of the type 70 head, will permit the latter to shift under the impulse of centrifugal force, thus presenting the upper case character in the printing position. Upon the retraction of the type-bar, the head drops back to its normal 75 position and the restoration of the trigger to its position in engagement with the head is insured by the contact of the resetting arm 39 with a fixed buffer ring 44, a portion of which is shown in Fig. 6. The depression of the trip frame 40, for the purpose stated, is effected through the medium of a case key 45, whose stem 46 is suitably guided in the carriage casing and is connected at its lower end to the case key lever 47 fulcrumed at its opposite end, as indicated at 48, and pivotally connected intermediate of its ends to the stud 43.

The case key 45 is normally retained in its elevated position by a spring 49 and is provided with a pin 50 engaged by a locking device or catch 51 when it is desired to hold the key in its depressed position for the purpose of printing upper case characters exclusively. For a more complete disclosure of 95 the mechanism just described, reference is made to the Fisher patent heretofore identified and also to Patent No. 708,213, and Re-issued Patent No. 11,848, both to R. J. Fisher.

The operative connection between the case key and the spacing rack 31 is effected in the following manner: In the back wall of the carriage casing 4 is secured a bearing sleeve 52, retained in place by a lock nut 53 and 105 constituting a support and bearing for a shaft rod 54, provided at its rear end with a head 55 engaging the rack 31. The inner end of the rod 54 is pivotally connected to the lower extremity of an arm 56, depending 110 from a rock shaft 57 disposed longitudinally of the carriage casing and mounted in brackets 58 extending from the rear wall thereof. Adjacent to one end of the shaft 57 the latter is provided with a forwardly extending arm 115 59 connected by a vertical link 60 with the rear extremity of a lever 61 fulcrumed in a post 62 upstanding from the bottom of the carriage. The lever 61 is extended to the front of the carriage, see Fig. 3, where its 120 extremity is pivotally connected to the stem 46 of the case key 45. It will now be seen that with the depression of the case key to reorganize the printing mechanism the shaft 57 will be rocked to swing the arm 56 to the 125 position indicated in dotted lines in Fig. 3 and thus draw back the shift rod 54, which will swing the spacing rack 31 to its operative position. The depression of the case key will thus be seen to simultaneously

change the feed and the case and obviously, as soon as the case key is released, its retraction by its spring will serve, through the intermediate connections, to throw back the 5 rack 31 to an inoperative position and thus restore the normal carriage feed. To insure the movement of the rack to its operative position, even though when actuated the projection 29 is opposite the point of one of 10 the teeth 30, the adjacent faces of said rack teeth 30 and the projection 29 are oppositely beveled, as shown in Fig. 9.

It is thought that the construction and 15 operation of the present embodiment of the invention will be clearly understood from the foregoing; but I wish to be distinctly understood as reserving the right to effect such changes, modifications and variations of the illustrated structure as may come 20 fairly within the scope of the protection prayed.

What I claim is—

1. In a typewriting machine, a platen and printing mechanism, relatively movable to 25 space the characters printed, an escapement controlling such movement and including an escapement rack, means for operating the escapement to effect normal spacing of the platen and printing mechanism, and a spacing rack extending in the direction of the relative movement of the platen and printing mechanism and coöperating with the escapement to cause exaggerated operation thereof for the purpose of exaggerating the 35 spacing.

2. In a typewriting machine, the combination with a platen and printing mechanism, relatively movable to letter space the writing, of feeding mechanism controlling such 40 movement and including a rack member and dogs alternately engaging the same for normal spacing and a plurality of devices disposed successively to retard the movement of one dog to exaggerate the relative movement 45 of the platen and printing mechanism incidental to the printing operation.

3. In a typewriting machine, the combination with a platen and printing mechanism, relatively movable, of feeding mechanism 50 controlling such movement and including a rack member and a pair of dogs coöperating therewith for normal spacing, and a spacing rack having a series of teeth arranged to effect the repeated retardation of one dog to exaggerate the relative movement 55 of the platen and printing mechanism.

4. In a typewriting machine, the combination with a platen and printing mechanism, relatively movable, of an escapement operated by the printing mechanism and including a rack member and a pair of dogs, and means for repeatedly retarding one of the dogs to repeatedly exaggerate the relative movement of the platen and printing mechanism incidental to the operation of the 65

latter, said means being movable into and out of operative position.

5. In a typewriting machine, the combination with a platen and printing mechanism, relatively movable, of an escapement 70 controlling such movement and including a rack element and a pair of dogs, and a series of devices arranged to successively retard one of the dogs to exaggerate the relative movement of the platen and printing mechanism, said devices being movable in unison into and out of operative position 75 and automatically brought into action when in operative position, by the relative movement of the platen and printing mechanism incidental to the operation of the latter.

6. In a typewriting machine, the combination with a platen and printing mechanism, relatively movable, of an escapement including 80 a rack member and a pair of dogs coöperating therewith, and a laterally shiftable spacing rack having teeth arranged to effect the repeated retardation of one of the dogs of the escapement.

7. In a typewriting machine, the combination with a platen and printing mechanism, relatively movable, of an escapement controlling such relative movement and including 90 a rack member, a spacing rack coöperating with the escapement to exaggerate such relative movement, and key operated means for effecting a coöperative relation between the escapement and the spacing rack.

8. In a typewriting machine, the combination with a platen and printing mechanism, relatively movable, of an escapement controlling such relative movement to letter space the writing and including a rack member, a spacing rack designed to coöperate 100 with the escapement to exaggerate the relative movement of the platen and printing mechanism, and a key for moving said spacing rack to its operative position.

9. In a typewriting machine, the combination with a platen and printing mechanism, relatively movable, of an escapement controlling such movement and including a rack member, and a swinging spacing rack arranged to coöperate with the escapement to 110 exaggerate the relative movement of the platen and printing mechanism.

10. In a typewriting machine, the combination with a platen and printing mechanism, relatively movable, of an escapement 120 controlling such movement and including a rack member, a swinging spacing rack arranged to coöperate with the escapement to exaggerate the relative movement of the platen and printing mechanism, and means 125 for swinging the spacing rack from one position to another.

11. In a typewriting machine, the combination with a traveling carriage and printing mechanism including keys, of an escape- 130

a trip arm at the opposite end of the rock-shaft, and a series of trips disposed to engage the trip arm.

26. In a typewriting machine, the combination with a carriage and an escapement controlling the movement thereof, of a trip arm operatively related to the escapement and having a pointed tooth, and a series of trips having the form of pointed teeth disposed to be successively engaged by the tooth of the trip arm to repeatedly effect a momentary retardation of an element of the escapement.

27. In a typewriting machine, the combination with a platen and printing mechanism, relatively movable, of an escapement controlling such movement and including a rack member, a laterally movable spacing rack coöperating with the escapement to exaggerate the movement, a rack shifting device slidably engaging the rack, and means for operating the shifting device to move the rack to its operative position.

28. In a typewriting machine, the combination with a platen and printing mechanism, relatively movable, of an escapement controlling such relative movement, a laterally movable spacing rack arranged to co-operate with the escapement to exaggerate the movement, a shifter for moving the rack to its operative position, a rock-shaft connected to the shifter to move the same, and a key operatively related to the rock-shaft.

29. The combination with a platen and printing mechanism relatively movable, one with respect to the other, of an escapement controlling such relative movement for normal spacing, and operated by the printing mechanism, and means brought into action repeatedly by the relative movement of the platen and printing mechanism, incidental to the operation of the latter, to repeatedly exaggerate the normal operation of the escapement and thereby effect a uniform exaggeration of the relative movement of the platen and printing mechanism.

30. The combination with a platen and printing mechanism relatively movable, one with respect to the other, in the direction of letter spacing, of an escapement, operated by the printing mechanism to cause uniform narrow spacing, and a series of devices brought into action by the relative movement of the platen and printing mechanism incidental to the operation of the printing mechanism to cause the exaggeration of the normal operation of the escapement and thereby effect an exaggeration of the relative movement of the platen and printing mechanism for uniform wide spacing.

31. In a typewriting machine, the combination with a movable carriage and printing mechanism, of an escapement controlling the movement of the carriage for normal spacing and operated by the printing mechanism, and

means brought into action repeatedly by the movement of the carriage incidental to the operation of the printing mechanism to repeatedly exaggerate the normal operation of the escapement and thereby effect a uniform 70 exaggeration of the carriage movement.

32. In a typewriting machine, the combination with a carriage, of an escapement rack, dog mechanism coöperating with the rack to control the movement of the carriage for uniform narrow spacing, normally inoperative means which, when in operative position, is brought into effective coöperative relation with the escapement mechanism by the movement of the carriage, to exaggerate the action of the escapement and thus permit exaggerated movement of the carriage for uniform wide spacing, and means for rendering said normally inoperative means operative.

33. In a typewriting machine, the combination with a movable carriage, of an escapement controlling the movement of the carriage for normal spacing, said escapement including a holding dog, a spacing dog and a rack member alternately engaged by said dogs, the spacing dog being normally engaged with the rack member to hold the carriage against movement, a key arranged to operate the escapement dogs to move the spacing dog out of engagement with the rack member and to move the holding dog into engagement with the said member, means operative upon the release of the key to advance the carriage, means operative upon the release of the key to withdraw the holding dog from the escapement member and thus permit the advance of the carriage and to move the spacing dog toward the rack member to arrest the carriage, a trip brought into coöperative relation with the spacing dog by the movement of the carriage to retard the movement of said spacing dog toward the rack member and to thus permit an exaggerated movement of the carriage before such movement is arrested by the engagement of a spacing dog with the rack member, and means operative to determine whether the trip shall or shall not operate as stated, said means including 110 a key or finger piece.

34. In a typewriting machine, the combination with a movable carriage, of an escapement wheel movable therewith, a pair of connected dogs also movable with the carriage and arranged to alternately engage the escapement wheel at opposite sides thereof to control the movements of the carriage, keys for operating the dogs, a series of trips on the frame of the typewriter, and a member extended from one of the dogs and arranged to be moved into engagement with the under sides of the trips by the advance of the carriage to repeatedly retard the movement of said dog to its engaging position.

ment controlling the movement of the carriage and including a rack member, and a series of devices brought into action successively by the movement of the carriage upon the depression of the printing keys and coöperating with the escapement to exaggerate the carriage movement.

12. In a typewriting machine, the combination with a traveling carriage, of an escapement movable therewith and including a rack member and a pair of dogs, and means mounted independently of the carriage and coöperating with the escapement to effect an exaggerated but uniform carriage feed.

13. In a typewriting machine, the combination with a movable carriage, of an escapement movable therewith and including a rack member and a pair of coöperating dogs, and a spacing rack mounted independently of the carriage and having teeth arranged successively to retard one of the escapement dogs for the purpose of exaggerating the carriage feed.

14. In a typewriting machine, the combination with printing mechanism and a movable carriage, of an escapement operated by the printing mechanism to control the step-by-step movement of the carriage and including a rack member and a pair of dogs, means coöperating with one of the dogs of the escapement to effect an exaggerated step-by-step feed of the carriage as the escapement is operated by the printing mechanism, and mechanism operative to determine whether said means shall or shall not operate.

15. In a typewriting machine, the combination with a traveling carriage and an escapement movable therewith and including a rack member and coöperating dogs, of a spacing rack mounted independently of the carriage and coöperating with the escapement to exaggerate the carriage feed, and means mounted on the carriage for moving the spacing rack to its operative position.

16. In a typewriting machine, the combination with a platen and printing mechanism, relatively movable, said printing mechanism including a case key, of an escapement controlling such relative movement and including a rack member and a pair of coöperating dogs, and means, movable to its operative position by the case key, for retarding the movement of an escapement dog to exaggerate the feed.

17. In a typewriting machine, the combination with a platen and printing mechanism, relatively movable, said printing mechanism including a case key, of an escapement controlling the normal relative movement of the platen and printing mechanism and including a rack member and a pair of coöperating dogs, a spacing rack designed to coöperate with the escapement to effect an exaggeration of the relative movement of the platen and printing mechanism, and means

operatively connecting the case key with the rack whereby the depression of said key will effect a change of case and of feed.

18. In a typewriting machine, the combination with a platen and printing mechanism, relatively movable in the direction of letter spacing, of an escapement controlling the normal letter space movements of the machine, a series of trips, and means operated by said trips for exaggerating the letter space movements.

19. In a typewriting machine, the combination with a platen and printing mechanism, relatively movable, of an escapement controlling the normal letter space movements, a trip arm operatively related to the escapement to effect an exaggerated feed, and a series of trips for operating the arm.

20. In a typewriting machine, the combination with a traveling carriage, of an escapement movable with the carriage, a trip arm likewise movable therewith and operatively related to the escapement, and a series of trips mounted independently of the carriage and arranged to coöperate with the trip arm.

21. In a typewriting machine, the combination with an escapement comprising a rack member and a pair of dogs coöperating therewith, of means for effecting the normal operation of the escapement, an arm operatively related to one of the dogs, and means for operating said arm to repeatedly retard the movement of the dog for the purpose of effecting an exaggerated operation of the escapement.

22. In a typewriting machine, the combination with an escapement including a rack member and coöperating dogs, of a trip arm operatively related to one of the dogs, and a series of trips disposed to engage the trip arm.

23. In a typewriting machine, the combination with an escapement including a rack member and coöperating dogs, of a rock-shaft coöperatively related to one of the dogs, a trip arm extended from one end of the rock-shaft, and a plurality of trips disposed to engage said arm.

24. In a typewriting machine, the combination with a movable carriage, of an escapement mounted on the carriage and including a rack member and coöperating dogs, a rock-shaft also mounted on the carriage and operatively related to one of the dogs, a trip arm extending from the rock-shaft, and a series of trips mounted independently of the carriage and disposed to engage the trip arm.

25. The combination with a typewriting machine, of an escapement including a rotary rack member and a pair of coöperating dogs, an arm extending from one of said dogs, a rock-shaft provided at one end with an arm coöperating with the arm first named,

tion and thus permit exaggerated or abnormal movement of the escapement wheel before the same is arrested by the dog.

35. In a typewriting machine, the combination with a carriage, of an escapement controlling the normal step-by-step advance of the carriage, carriage release mechanism arranged to operate the escapement to permit the free advance of the carriage, and means independent of the release mechanism and brought into action repeatedly and automatically during and by the advance of the carriage to exaggerate the normal action of the escapement.

36. In a typewriting machine, the combination with a carriage, an escapement controlling the normal step-by-step advance thereof, carriage release mechanism, and means independent of the release mechanism and brought into action by the movement of the carriage to exaggerate each normal action of the escapement during the carriage advance and to thus cause uniform wide or abnormal spacing of the characters printed.

37. In a typewriting machine, the combination with a carriage, of an escapement controlling the normal step-by-step advance of said carriage, carriage release mechanism, a series of devices mounted independently of the release mechanism and carriage, and means presented to successive devices by the movement of the carriage and coöoperating with said devices to repeatedly exaggerate the action of the escapement during the carriage advance and to thus cause uniform wide or abnormal spacing of the characters printed.

38. In a typewriting machine, the combination with a carriage, of an escapement controlling the normal step-by-step advance thereof, carriage release mechanism and a series of devices mounted independently of

the release mechanism and movable into and out of operative position, and means co-acting with said devices to exaggerate 45 the action of the escapement and thus cause uniform wide or abnormal spacing of the characters printed.

39. In a typewriting machine, the combination with a carriage, of an escapement including a rack and dogs controlling the normal step-by-step advance of the carriage, release mechanism operative to disengage the rack and dogs and thus release the carriage for free movement, and means separate from 55 and independent of such release mechanism and including a series of devices, said means being brought into coöperative relation with the escapement by the movement of the carriage during its step-by-step advance to 60 cause exaggerated operations of the escapement and thus effect wide spacing of characters printed.

40. In a typewriter, the combination with a platen and printing mechanism, relatively 65 movable, of an escapement controlling such movement and operated by the printing mechanism, and means for repeatedly exaggerating the relative movement of the platen and printing mechanism incidental 70 to the operation of the latter, said means including a series of devices which when in operative position are brought into action automatically, one of said devices being variable to render the same operative or 75 non-operative.

In testimony that I claim the foregoing as my own, I have hereto affixed my signature in the presence of two witnesses.

JOHN A. SMITH.
